(57) **CLAIM**

The ornamental design for a pipe fitting, as shown and described.

DESCRIPTION

- 3. Pipe fitting
- 3.1 : Perspective
- 3.2 : Top
- 3.3 : Bottom
- 3.4 : Front
- 3.5 : Back
- 3.6 : Left
- 3.7 : Right
- 3.8 : Exploded

A pipe fitting comprising an in-line thermal isolator with a cylindrical insulating body, a projecting inlet end and a projecting outlet end and isolated component insert for the same.
